UNITED STATES PATENT OFFICE

167,743

COMBINATION HEATING AND COOLING PAD

Jerome J. Dorfman, New York, N. Y.

Application November 19, 1951, Serial No. 17,470

Term of patent 7 years

(Cl. D83—1)

To all whom it may concern:

Be it known that I, Jerome J. Dorfman, a citizen of the United States of America, residing in New York, county of New York, and State of New York, have invented a new, original, and ornamental Design for a Combination Heating and Cooling Pad, of which the following is a specification, reference being had to the accompanying drawing, forming part thereof.

Fig. 1 is a plan view of a combination heating and cooling pad, showing my new design.

Fig. 2 is an edge view thereof.

The other side is like the side shown in Fig. 1.

I claim:

The ornamental design for a combination heat-

ing and cooling pad, substantially as shown and described.

JEROME J. DORFMAN.
